ILLUMINATING DEVICE

Russell L. Hohl, New York, N. Y.

Application August 1, 1936, Serial No. 93,852

10 Claims. (Cl. 240—1)

My invention relates to illuminating devices, and has among its objects the provision of a support for an electric lamp providing both a wiring conduit for the leads to the lamp and a reflector for the lamp.

The invention will be best understood from the following description when read in the light of the accompanying drawings of several embodiments of the invention, the scope of which latter will be more particularly pointed out in the appended claims.

In the drawings:

Fig. 1 is a longitudinal section of an illuminating device constructed according to the invention, with parts in elevation, this figure corresponding to a section on the lines 1—1 of Figs. 2 and 3 on a reduced scale;

Fig. 2 is a section on the line 2—2 of Fig. 3, with parts in elevation;

Fig. 3 is a bottom view of a fragment of the illuminating device according to Figs. 1 and 2, with parts omitted;

Fig. 4 is a fragment, on an enlarged scale of the illuminating device shown by Fig. 1 and corresponds to a section on the lines 1—1 of Figs. 2 and 3;

Fig. 5 illustrates a detail, on an enlarged scale;

Fig. 6 is a bottom view of the lamp socket and wiring base;

Fig. 7 is a section on the line 7—7 of Fig. 6;

Fig. 8 is a section on the line 8—8 of Fig. 7;

Fig. 9 is a side elevation of the spring clip of the wiring base;

Fig. 10 is a plan of the clip according to Fig. 9;

Fig. 11 is a side elevation of the end portion of the lamp;

Fig. 12 is an end view of the lamp according to Fig. 11;

Figs. 13 and 14 are respectively an elevation and edge view of an end cover plate for the reflector and wiring conduit;

Fig. 15 is a schematic wiring diagram;

Figs. 16, 17, 18, 19, 20 and 21 illustrate modified forms of the invention;

Fig. 22 is a side elevation of a fragment of the device according to Fig. 18; and

Fig. 23 is a side elevation of a fragment of the device according to Fig. 21.

Referring particularly to Figs. 1 to 15, the support for the lamp comprises a base portion in the form of an elongated channel-shaped extrusion having a web 1 and side flanges 3, this extrusion being adapted to be secured to a wall, ceiling, or other support S by suitable fastening

members F, such as nails, extending through suitably formed openings in the web.

As illustrated, the web of this extrusion is formed on its inner side with a pair of spaced, longitudinally extending ribs 5 and 7, on the edges of which are adapted to rest the "bottom" surfaces of the base portions 9 of wiring bases for lamps L. These wiring bases preferably extend from one flange 3 to the other of the extrusion. The spaces between the two ribs 5 and 7 and between each of these and the adjacent flange 3 form channels or grooves for receiving the lead wires W for energizing the lamps and for receiving such auxiliary lead wires W' as it may be desired to conduct, which lead wires W' may be used for a different group of lamps than those energized by the lead wires W.

The wiring bases are best shown by Figs. 6 to 10 inclusive. Each wiring base has a body formed of insulating material, and comprises a projecting portion 11 extending from the base portion 9 at one side thereof. The entire body is hollowed out to provide a cavity 13 having an opening 15 at the end of the projecting portion 11. In the cavity 13 is a metallic member comprising a pair of spring clips 17 formed integrally with the base 19, which base includes a projection 21 secured by a tubular rivet 23 to a cover 25 of insulating material for the "bottom" opening of the cavity of the wiring base. The opening of the tubular rivet 23 is screw-threaded for receiving a screw 27 for connecting the lead wires electrically to the spring clips 17. The covers 25 are secured to the body of the wiring base by tubular rivets 29.

The lamps L, which are carried by the wiring bases, have elongated tubular bulbs, each bulb at opposite ends thereof carrying a terminal cap 31 (Fig. 11) having an inwardly flaring socket 33. The filaments (not shown) of the lamps extend lengthwise of the bulbs from one terminal cap 31 to the other. This construction of the lamp being well known need not be further described.

For supporting the lamps on the wiring bases, there is associated with each pair of spring clips 17 a lamp socket comprising a shallow cup 35, of insulating material, having side walls 37. Internally of this cup is a metal plate 39 having at its edges teeth 41 which are snapped under the bead 43 carried by the interior surfaces of the side walls 37 of the cup. The center portion of the plate is struck up to form a split resilient stud having the prongs 45, this stud being adapted to snap into the socket 33 in the terminal

caps of the lamps, the arrangement being closely like that of the ordinary snap fastener. The plate 39 is further shaped to form a projection 47 which extends through an opening 48 in the 5 side walls 37 of the cup 35. This projection, for giving it rigidity, is formed with marginal walls 51, the end of the projection being rounded so that it may readily be snapped between the 10 spring clips 17. As illustrated, the spring clips 15 have hooked ends 53, while the projection 47 is formed to provide notched portions 55 into which the hooked ends of the clips snap, so that the 20 projections 47 of the lamp sockets cannot be withdrawn after they are snapped between the 25 clips.

The lamp socket and wiring base, with the exception of the last mentioned feature involving the notches 55 and the hooked ends 53 of the spring clips, is well known and need not be further described. It will be observed however from Fig. 7 that, as shown, the overall thickness of the projection 47 of the lamp socket is of less width than the corresponding width of the hollowed out portion of the projection 11 of the wiring base, 25 and that this construction permits the lamp sockets to be slightly tilted or slid from right to left, as viewed in Fig. 7, to enable the split studs of the lamp sockets to be snapped into the sockets 33 of the terminal caps of the lamps when the 30 wiring bases are assembled with the device, as will hereinafter be more fully described.

The flanges 3 of the base extrusion, as best illustrated in Figs. 2 and 5, have thickened lower edge portions 57 provided with longitudinally 35 extending grooves 59. Into these grooves fit the upper edge portions of the side walls 61 of the combined wiring-base retaining and reflecting members, which latter are also in the form of elongated extrusions. Preferably both extrusions 40 are made of aluminum, or high content aluminum alloy, such as "duralumin", having the relatively soft properties of aluminum. Preferably the side walls of the grooves 59 are formed with longitudinally extending grooves 63 to provide one or 45 more raised surfaces 65 which contact with the sides of the edge portions of the walls 61, and the metal of these parts, being soft, galls when the parts are forced together, this affording sufficient friction to prevent separation of the parts 50 except when they tend to be separated with considerable force.

As illustrated in Fig. 2, the combined wiring-base retaining portion and reflector, which also forms a cover for the base extrusion, is made in two parts each of which has an arcuate portion 67 the adjacent ends of which are formed 55 with ribs 69 which abut in the assembled device and the edges of which engage with the base portion 9 of the wiring base to hold it against the 60 ribs 5 and 7. The adjacent edges of the arcuate portions of the extrusions are notched to form openings 71 (Fig. 3) through which the projecting portions 11 of the wiring bases extend. Conveniently, the arcuate portions 67 of the 65 extrusions are formed on their upper surfaces with longitudinally extending grooves 73 of V-shaped cross-section, as illustrated in Fig. 2, and by sawing inward with a hack-saw from the edges of the arcuate portions to these grooves the parts 70 between the saw cuts may be readily broken off at the V-shaped grooves to form the notches which, when the arcuate portions are placed together, form the openings 71.

As illustrated, the side wall 61 of each reflector 75 extrusion above described is formed with a thick-

ened portion 75 which is provided with a longitudinally extending groove 77 the upper portion of which is inclined outwardly, as indicated at 79, to open on the exterior of the side walls. If desired, communicating with the groove 77 may be provided holes 81 for the purpose of ventilating the interior of the conduit formed by the extrusions.

In the assembled device the wiring-bases may be placed back to back to provide for supporting a plurality of axially aligned lamps. Before assembling the extrusions the lead wires W are connected to the terminal screws 27 in the manner indicated in Fig. 15.

If desired, the ends of the assembled extrusions may be closed by plates 83 (Figs. 1, 13 and 14), these plates having screw holes 85 so positioned that the shanks of the screws inserted through them will enter the open ends of the grooves 77. The material of the extrusion being soft, the screws will "self tap" into the side walls of the groove.

Various modifications of the invention heretofore described may be made. When the lamps are to be placed at an interior corner the arrangement shown by Figs. 16 or 19 may be employed. When placed at an exterior corner the arrangement shown by Fig. 17 may be employed, and when placed on the side of a wall the arrangement shown by Fig. 20 may be employed. All these 30 arrangements employ the same base extrusion hereinbefore described, and the reflector members are secured to that extrusion in the same way.

Referring to Fig. 16, the extrusions which retain the wiring-bases and form the reflector, as 35 heretofore described, may be made in two parts. As shown, the side wall 86 of the right hand extrusion does not extend below the reflector portion 67, while the side wall 88 of the left hand extrusion has an arcuate extension 87 at its lower 40 end, so that these right and left hand members together form a reflector which will reflect light at an angle downwardly from the vertical wall of the support.

Referring particularly to Fig. 19, the rib 7 of 45 the base extrusion is formed with a longitudinally extending groove 89 opening on the outer surface of the web 1 of that extrusion, the opposite walls of which groove are formed with one or more of the longitudinally extending grooves 63 illustrated in Fig. 5. Into this groove 89 is forced the end edge of a vertical web 91 of a bracket member which has the portions 93 and 95 fitting the interior corner of the supporting structure and secured thereto. This bracket member may be 55 formed of short lengths of an extrusion of the same metal as the other extrusions, it being understood that a plurality of bracket members will be distributed along the conduit formed by the other extrusions. In the modification shown 60 by Fig. 19, the side walls 61 of the reflector extrusions do not extend below the arcuate portions 67, both of these extrusions being like the right hand reflector extrusion of Fig. 16.

In the modification shown by Fig. 17 the base 65 extrusion is secured to the support by means of an elongated extrusion having the side walls 97. This extrusion, as shown, is formed with a web 99 integral with the side walls. The web is so formed as to provide a V-shaped notch 101 which 70 engages the corner of the support and is also so formed as to provide a downwardly extending rib 103 which enters the longitudinally extending groove 89 in the web 1 of the base extrusion, which web 1 rests against the lower edges of 75

the side walls 97. In this way, due to the galling action between the side walls of the groove 89 and the rib 103, the parts are held securely in assembled relation. It will be observed that the reflector members as well as the base member of this modification are like those of the modification shown by Fig. 19.

Referring to Fig. 20, the base and reflector portions of the device are like those shown by Fig. 16. The conduit and reflector are held to the support by angle-shaped brackets each of which has a horizontal leg 105 and a vertical leg 107, the latter of which is secured to the supports. At the end of the leg 105 is a downwardly extending flat tab 109 which enters the longitudinally extending groove 89 in the base member so that the parts are held in assembled relation. It will be understood that the brackets having the tabs 109 may be cut as short lengths from long extrusions made of the same metal as the other extrusions. It will be observed that other than in respect to the supporting bracket the device according to Fig. 20 is like that shown by Fig. 16.

The arrangement shown by Fig. 18 is similar to that shown by Fig. 2, except that provision is made for an auxiliary reflector. This auxiliary reflector, as shown, comprises an extrusion having the arcuate portions 111 which are joined by a thickened portion 113 having a longitudinally extending groove 115 on its upper side, the opposite walls of this groove each being formed with one or more longitudinally extending grooves 63, illustrated in Fig. 5. The auxiliary reflector is held to the end portions of the side walls 61 of the main reflector by Y-shaped brackets 117, the upper edges of the legs of which brackets are formed with thickened portions 119 having longitudinally extending grooves 121 opening on their upper sides, each of these grooves 121 having grooved side walls like those heretofore described. The lower edges of the side walls 61 of the main reflector are received in these grooves 121 and frictionally retained therein. The stem portions 123 of the Y-shaped brackets similarly fit into the groove 115 so that the brackets will be firmly frictionally secured to the auxiliary reflector. It will be understood that these V-shaped brackets may be cut as short lengths from long extrusions of the same metal as the other extrusions.

Figs. 21 and 23 show the manner in which the auxiliary reflector may be connected to a device having reflector portions like that shown by Figs. 2 and 17. In this arrangement the brackets secured to the auxiliary reflector have vertical webs 124 carried by horizontal portions 125. At the ends of the horizontal portions are upwardly extending inclined portions 127 provided with hooked ends 129 of the shape shown in Fig. 21, so as to conform to the exterior surfaces of the side walls 69 of the reflector extrusions and fit into the grooves 77 and 79 of said side walls. The brackets for securing the auxiliary reflector, like the Y-shaped brackets of Figs. 18 and 22, may be formed of short lengths sawed from an elongated extrusion of the same metal as the other extrusions.

It will thus be observed that the several extrusions described may be assembled to fit a variety of uses, in all cases the parts being secured by a friction fit. Preferably all the extrusions are formed of soft metal, as described, but, if desired, only one of each pair of extrusions having a friction tongue and groove fit need be formed of such metal. The grooves 77, 79, as illustrated,

are not provided with grooved side walls as are the grooves 63, 89, 121 and 123, but they may be so formed if desired.

It will be understood that within the scope of the appended claims wide deviations may be made from the forms of the invention above described without departing from the spirit of the invention.

I claim.

1. A device of the character described having an elongated base member of channel-shaped cross-section adapted to contain a lamp wiring base, a combined cover and reflector part having an opening for a projecting, lamp-supporting, lamp-contact-carrying part carried by such wiring base, said cover and reflector part being formed of two longitudinally extending portions having closely adjacent edges intermediate the width of said base member, which portions are independently carried by said base member adjacent the longitudinal edges thereof, whereby reflectors of different shape may be had by substituting for one or the other of said portions of said cover and reflector part a different portion of changed shape.

2. A device of the character described having an elongated base member of channel-shaped cross-section adapted to contain a lamp wiring base, a combined cover and reflector part for the channel opening of said base member, which cover has an opening for a projecting, lamp-supporting, lamp-contact-carrying part carried by said wiring base, said cover being formed of two longitudinally extending parts separately carried by said base member adjacent the opposite edges thereof, respectively, which parts have closely adjacent longitudinally extending edges intermediate the width of said base member, at least one of said cover parts being notched at such edge thereof for forming said opening of said cover.

3. A device of the character described having an elongated base member of channel-shaped cross-section adapted to contain a lamp wiring base, a cover for the channel opening of said base member, which cover has an opening for a projecting, lamp-supporting, lamp-contact-carrying part carried by said wiring base, said cover being formed of two longitudinally extending parts separately carried by said base member adjacent the opposite edges thereof, respectively, which parts have closely adjacent longitudinally extending edges intermediate the width of said base member, at least one of said cover parts being notched at such edge thereof for forming said opening of said cover, which cover part has a longitudinally extending portion of line-like width back of said edge providing a frangible line, whereby said notch may be formed by making spaced cuts in said part from said edge back to said line and breaking off at said line the metal between said cuts.

4. A device of the character described having an elongated base member of channel-shaped cross-section adapted to contain a lamp wiring base, a cover for the channel opening of said base member, which cover has an opening for a projecting, lamp-supporting, lamp-contact-carrying part carried by said wiring base, said cover being formed of two longitudinally extending parts separately carried by said base member adjacent the opposite edges thereof, respectively, which parts have closely adjacent longitudinally extending edges intermediate the width of said base member, said cover parts having complementary notches at said edges thereof forming said open-

ing of said cover, which cover parts have longitudinally extending V-shaped grooves back of said edges providing frangible lines, whereby said notches may be formed by making spaced cuts in 5 said parts from said edges back to said lines and breaking off at said lines the metal between said cuts.

5. A device of the character described having an elongated base of channel-shaped cross-section, a cover secured to said base for closing the channel opening thereof, which channel is adapted to contain lamp wiring bases and the wiring therefor, and which cover has openings for projecting, lamp-supporting, lamp-contact-carrying 10 parts carried by said wiring bases, said base being formed with a longitudinally extending groove opening on the exterior thereof, and a support for said base adapted to be secured to a wall or the like having a tongue adapted to enter said 15 groove and be frictionally retained therein.

6. A device of the character described having an elongated base member of channel-shaped cross-section to provide a web and opposite flanges, the interior side of said web being formed 20 with spaced longitudinally extending raised ribs, a wiring base having a binding terminal at its under side, the latter being adapted to rest on said ribs with the binding terminal between said ribs, and means engaging said wiring base for 25 holding it against said ribs comprising a combined reflector and cover part carried by said flanges, which part and flanges are provided with cooperating tongues and grooves directed toward said web whereby said part may be frictionally secured 30 to said flanges by movement of said part toward said wiring base.

7. A device of the character described having an elongated base member of channel-shaped cross-section to provide a web and opposite flanges, the interior side of said web being formed 35 with spaced longitudinally extending raised ribs, a wiring base having a binding terminal at its under side, the latter being adapted to rest on said ribs with the binding terminal between said ribs and with the opposite sides of the wiring 40 base coating with the opposite flanges of said base member for preventing transverse shifting 45

of said wiring base, and means engaging said wiring base for holding it against said ribs comprising a combined reflector and cover part carried by said flanges, which part and flanges are provided with cooperating tongues and grooves directed toward said web whereby said part may be frictionally secured to said flanges by movement 5 of said part toward said wiring base.

8. A device of the character described having a longitudinally extending base member of channel-shaped cross-section to provide a web and opposite flanges, a lamp wiring base adapted to be received within the channel of said base member and operatively to rest upon the interior surface of said web, the outer edges of said flanges 10 carrying separate parts, respectively, which parts cooperate to form a reflector and a cover for the channel opening of said base member, each flange and said part carried thereby being formed one with a groove and the other with a tongue frictionally received by such groove whereby the parts may be assembled with the flanges by pressing the parts directly toward the base member, at least one of said parts carried by said flanges 15 being constructed to engage with the side of the 20 wiring base opposite said web.

9. In a device of the character described, a longitudinally extending base part of channel-shaped cross-section, a longitudinally extending cover part for closing the channel opening of 25 said base part, one of said parts having a lateral wall provided with ventilating openings and being formed with a longitudinally extending flange 30 opposed to said openings in spaced relation to said lateral wall.

10. In a device of the character described, a longitudinally extending base part of channel-shaped cross-section, a longitudinally extending cover part for closing the channel opening of said base part, one of said parts having a lateral wall and being formed with a longitudinally extending 35 upwardly projecting flange in spaced relation to said wall to provide an upwardly opening groove, a reflector below said cover part, and means for suspending said reflector having a hooked portion received by said groove.

45 RUSSELL L. HOHL.
